UNITED STATES PATENT OFFICE.

RAYMOND V. BROMLEY, OF WASHINGTON, PENNSYLVANIA, ASSIGNOR TO HAZEL-
ATLAS GLASS COMPANY, OF WHEELING, WEST VIRGINIA, A CORPORATION OF WEST
VIRGINIA.

DESIGN FOR A GLASS JAR.

Application filed February 16, 1924. Serial No. 8,648. Term of patent 14 years.

To all whom it may concern:

Be it known that I, RAYMOND V. BROMLEY, a citizen of the United States, residing at Washington, in the county of Washington and State of Pennsylvania, have invented a new, original, and ornamental Design for Glass Jars, of which the following is a specification, reference being had to the accompanying drawing, forming part thereof.

Figure 1 is a view of the jar in elevation;

and

Figure 2 is a plan view thereof.

I claim:

The ornamental design for a glass jar, as shown.

RAYMOND V. BROMLEY.
